UNITED STATES PATENT OFFICE.

MARVIN A. MATHEWSON, OF ELMIRA, NEW YORK.

STAND FOR SHINING SHOES.

1,236,198.

Specification of Letters Patent.

Patented Aug. 7, 1917.

Application filed May 3, 1917. Serial No. 166,109.

To all whom it may concern:

Be it known that I, MARVIN A. MATHEWSON, a citizen of the United States, and a resident of Elmira, in the county of Chemung and State of New York, have invented a new and Improved Stand for Shining Shoes, of which the following is a full, clear, and exact description.

My invention relates to movable foot supports on the stand so as to facilitate the engagement of the seat by a person whose shoes are to be shined and also to eliminate the danger of soiling the clothing of a person while getting on or off the stand.

An object of the invention is to provide a simple, efficient and inexpensive device which, in addition to serving as a foot rest will also serve as a step for facilitating the walking of a person on to or from the stand.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a perspective view of a stand provided with an embodiment of my invention;

Fig. 2 is a side elevation of the stand, a portion of the end wall of the stand being broken out to show the details of construction;

Fig. 3 is a top plan view, a portion of which is shown in a horizontal section on line 3-3, Fig. 4; and

Fig. 4 is a section on line 4-4, Fig. 3, the foot supports in this figure being shown in the position when serving as a step.

Referring to the drawings, the stand is shown to be provided with individual seats 5-5. If desired, a bench may be used in lieu thereof. Where individual seats are used as shown, each chair is provided with pairs of foot rests or supports 6. Where a bench is used such foot supports are provided at suitable intervals. Each pair of foot supports is united by a shaft 7 below the foot platform 8 and is mounted to revolve in suitable bearings 9 depending from the platform 8.

The major part of the weight of the foot rests is to one side of the axis of the shaft 7.

In consequence the foot rests tend to swing from the vertical or operative position, shown in Fig. 2 in full lines, to the horizontal position, shown in dotted lines in the same figure.

To allow the movement of the foot rests, slots 10 are provided in the foot platform. The foot rests on the shaft 7 are overbalanced by a counterweight 11 adjustably mounted on an arm 12 extending from the shaft 7. The counterweight tends to maintain the foot rests in operative position.

To prevent the displacement of the foot rests when in operative position, spring actuated latches 13 are provided for engaging each of the foot rests of the pair, thereby preventing the additional weight applied by the person whose shoes are to be shined from displacing the foot rests. The two latches are connected by a rod 14 which is connected to one arm of a crank lever 15, the other arm of which is connected to a rod 16, said rod in turn being connected to a pedal 17. By operating the pedal the latches 13 are withdrawn from engagement with the foot rests and the same can be moved from the position shown in full lines to that shown in dotted lines in Figs. 2 and 3. To prevent the displacement of the foot rests under the action of the counterweight from the position shown in dotted lines in the said figure to that shown in full lines in the same figure, spring-actuated latches 18 are provided similar to the latches 13, also connected by a rod 19 which is connected to the rod 16 by a bell-crank lever 20 in a manner such as has been referred to with reference to the bell-crank lever 15.

The foot rests 6, serving the same seat 5 are united by a board 21 which serves as a step when the foot rests are in the inoperative position and locked thereat by the latches 18. This step facilitates the mounting of the stand. Further, it clears the foot platform 8 from the foot rests during the time a person is mounting on the chair, thereby eliminating danger of soiling the person's clothes.

After the person is seated, by applying pressure to the foot pedal 17 the latches 18 are disengaged from the foot rests and the counterweight 11 swings them to the operative position, the latches 13 allowing the foot rests to pass to their operative position and become locked in said position auto- 110

matically. As soon as the shining of the shoes is terminated, by applying pressure on the pedal 17 the latches 13 are disengaged from the foot rests and they can be moved 5 to the inoperative position where they will be automatically retained by the latches 18 until the foot pedal is again operated as described. Thus, it will be seen that a person can mount the stand without any danger of 10 having the clothes soiled by the foot rests, and, further, the mounting and dismounting of the stand by the person is facilitated by the provision of the board 21 on the foot rests.

15 I claim:

1. A stand for shining shoes, comprising, a seat, foot rests associated with the seat and mounted to swing to and from the seat, gravitationally-operable means associated 20 with the foot rests and normally tending to maintain said foot rests in an operative position relative to the seat, means for locking the foot rests in the operative or in the inoperative position, and means for operating 25 said locking means.
2. A stand for shining shoes, comprising,—a seat, a foot platform, foot rests mounted to swing below the platform away from the seat, means overbalancing the foot 30 rests and normally tending to maintain the same in the operative position, means for locking said foot rests in the operative or in the inoperative position, and a member joining the foot rests and adapted to form a step 35 when the foot rests are in the inoperative position, substantially as and for the purpose set forth.

3. A stand for shining shoes, comprising,—a seat, a foot platform, foot rests mounted pivotally below the platform 40 whereby said foot rests may be maintained above or below the level of the platform, means for locking the foot rests above and below the level of the platform, and a member uniting the two foot rests and adapted to 45 form a step for the platform when said foot rests are below the level of the platform.

4. A stand for shining shoes, comprising,—a seat, a foot platform, foot rests associated with the platform and mounted to 50 swing to and from the seat, and above or below the level of the foot platform, balancing means associated with the foot rests and normally tending to maintain said foot rests above the level of the platform, locking 55 means adapted to engage automatically the foot rests in their position above or below the level of the platform, means for operating the locking means, and a member associated with the foot rests and adapted to 60 form a step for the platform when said foot rests are in the locked position below the level of the platform.

5. A stand for shining shoes, comprising,—a seat, a foot platform, movable foot 65 rests adapted to be brought above or below the level of the foot platform, means for locking the foot rests in their position above or below the foot platform, and a member associated with the foot rests and adapted to 70 form a step for the foot platform when said foot rests are in a position below the level of the foot platform.

MARVIN A. MATHIEUWSON.
